CLAIM

The ornamental design for a CT radiography apparatus as shown and described.

DESCRIPTION

FIG. 1 is a front side elevated perspective view of a CT radiography apparatus in an imaging position;

FIG. 2 is a front plan view thereof;

FIG. 3 is a first side plan view thereof;

FIG. 4 is a rear plan view thereof;

FIG. 5 is the other side plan view thereof;

FIG. 6 is a top view thereof;

FIG. 7 is a bottom view thereof;

FIG. 8 is another front side perspective view;

FIG. 9 is a rear perspective view; and,

FIG. 10 is another rear perspective view.
